UNITED STATES PATENT OFFICE.

ALBERT S. MICHELSON, OF AKRON, OHIO, ASSIGNOR TO THE AKRON RUBBER MOLD AND MACHINE COMPANY, OF AKRON, OHIO, A CORPORATION OF OHIO.

DESIGN FOR A TIRE.

Application filed September 28, 1926. Serial No. 19,193. Term of patent 14 years.

To all whom it may concern:

Be it known that I, ALBERT S. MICHELSON, a citizen of the United States, residing at Akron, in the county of Summit and State of Ohio, have invented a new, original, and ornamental Design for a Tire, of which the following is a specification, reference being had to the accompanying drawings forming a part thereof.

In the drawings:

Figure 1 is a plan view looking upon a section of a tire showing my new design; and

Figure 2 is a cross-section on the line 2—2 of Figure 1.

I claim:

The ornamental design for a tire as shown.

ALBERT S. MICHELSON.
